PAUL E. KLEINEBERG, OF EASTON, PENNSYLVANIA, ASSIGNOR TO AMERICAN ASSEMBLING MACHINE COMPANY, A CORPORATION OF DELAWARE

BOOKBINDER STITCHER

Application filed October 28, 1930. Serial No. 491,700.

One of the several ways in which the leaves or signatures of a book may be joined together, in the binding thereof, is by the driving of wire staples through the signatures, clinching the ends of the staple fast against the paper after being driven therethrough. This has been accomplished in the use of a machine having a reciprocating member or head traveling parallel to the books to be bound and carrying means for forming, driving and clinching three staples. This character of machine had the disadvantage that the spacing of the staples with reference to each other and to the book was fixed; in order 10 to permit the stapling of books of more than one size it was customary to space the three staples at different distances apart; for example, the fixed distance between the first and second staple might be approximately 15 $4\frac{1}{2}$ inches while the distance between the second and third staples might be $2\frac{3}{4}$ inches. By using this fixed spacing, the two staples more widely apart might be used for a relatively small book while the two staples more 20 closely arranged could be used for a still smaller book. Not only is the utility of such a machine limited by the fixed spacing of the staples, but the fact that three staples are formed and driven at one time imposes an 25 undesirable shock to the machine, either compelling the use of massive parts or subjecting the machine to undesirable wear.

In my improved machine I use a plurality of stitcher heads, each reciprocating and each 30 adapted to the forming, driving and clinching of but a single staple; and I so arrange these three heads that they may be independently timed so as to grip the books at any desired point, driving the staple therethrough with 35 complete independence of the point at which other staples may be driven.

Stitchers of this general character are preferably used as part of a series of machines which carry the books through the successive 40 processes of assembly, stitching and covering. In any event the books are to be carried through the stitchers by a conveyor, such conveyor preferably consisting of a chain having pins which project laterally therefrom 45 at definite intervals, say 16 inches apart.

Such a conveyor chain is carried along a chain race and at the side of a horizontal plate or book race along which the books are pushed by the pins on the conveyor chain, standing upright with the back edges of the 50 pages resting on the book race plate. I employ a common source of power for the conveyor chain and for the stitcher mechanisms and provide means by which the actuating of the several heads may be adjusted with reference to the chain, the source of power and 55 each other.

It will be understood that in such an arrangement, each pin on the conveyor chain will push before it a book to be stitched. The 60 chain has a uniform and continuous movement. In my machine, when the book reaches a predetermined position at the first stitcher unit, the mechanism of that unit grips the lower edges of the book, holding them firmly; 65 my mechanism is so arranged that this gripping action takes place when the reciprocating head and the conveyor propelled book are traveling forward at the same speed, the speed of the head immediately increasing so 70 as to draw the book away from the propelling conveyor pin so as to assure a control of the book movement by the traveling head itself. While in this gripped condition the machine forms, drives and clinches a staple 75 in the predetermined and desired portion of the book-edge.

By reason of the adjustable features I have introduced into my multiple-head stitcher, I 80 am enabled to place and drive the staples in any desired order and in any desired position on the back edge of the book, a characteristic action heretofore unknown in machines of this character. As each stitcher unit is like its fellows, all are interchangeable and any 85 one may be withdrawn from service for repairs or other purposes without putting the entire stitching mechanism out of action.

The above and other features, as will hereinafter appear, are fully described in the following specifications and shown in the accompanying drawing, in which Fig. 1 is a side elevation of two units of my stitcher mechanisms while Figs. 2 and 3 show two forms of cooperating coupling discs utilized 90 95 100

by me in the independent timing of the operations of the several units. In Fig. 1 my invention is illustrated in the use of two stitching units 1, 1, placed side by side and contiguous to the book guide 2, the book race 3 and the conveyor chain-race 4. The gear wheel 5 is a part of the chain of gears connected to a main driving shaft from which the conveyor chain is also driven. It is thus evident that the speed of travel of the chain and the speed of travel of the gear wheel 5 bear a definite relationship and timing to each other. The gear wheel 5 is mounted loosely upon the shaft 6 and drives such shaft 15 by being bolted to a coupling plate 7 keyed to the shaft 6. The gear wheel 5 is in effect another coupling plate. Coupling plates 5 and 7, illustrated in Figs. 3 and 2, respectively, are preferably formed with arcuate slots 20 5a and 5b, in the case of the gear wheel, and 7a and 7b in the case of the fixed coupler. Through the use of bolts, 8, 8, these two coupling plates may be clamped together in any desired relationship, even to the extent of a 25 complete 360 degrees. The hub of the coupling 7 is preferably squared, as shown at 7c, Fig. 2, to permit that coupling plate and its shaft 6 to be turned to the desired relationship to the gear wheel 5, by means of a suitable wrench.

In like manner the shaft 6a of the second unit, may be adjusted with reference to the shaft 6 of the first unit, through the shifting of the coupler 10 on the second unit with respect to the coupler 9 of the first unit, after which these two couplings are to be clamped firmly together. In similar manner, a corresponding shaft of a third unit may be clamped in adjusted position with reference 40 to the shaft 6a of the second unit.

As will be seen from the drawing, a mitre gear 11 on shaft 6 drives a gear 12 on a jack shaft 13 running at right angles to the shaft 6. On the shaft 13 is a crank 14 to which is attached a connecting rod 15 extending to the mid-portion of a lever arm 16 pivoted at 45 17. It will be seen that in the position of these parts in the first or lefthand unit of the drawing, the reciprocating head 18, carrying the various mechanisms for forming, driving and clinching a staple, is in its extreme lefthand position on its runway 19. This head 18 also carries the devices for clamping the book to the head, preparatory to the stapling operation and the parts are so arranged and adjusted that the clamping action takes place shortly after the crank arm has moved upwardly from the position shown, at a time when the head 18 and the book 20 are moving 50 at the same speed. It will also be seen that in the position of the crank arm 14, shown in the drawing, the head 18 is momentarily stationary and that as the crank arm 14 rises to a point at right angles to the position 55 shown, the speed of the head 18 will progres-

sively increase. This means, of course, that as soon as the clamping of the book to the head is effected, the book will be drawn away from the pin on the conveyor chain which had theretofore been advancing the book 70 along the book race; this takes the book out of the control of the conveyor and makes its travel dependent upon the speed of the head. After the staple has been driven and clinched, the book is unclamped and momentarily slackens 75 its speed until overtaken by its conveyor pin which thereupon carries the book forward for operation by the second unit and later by the third unit of the stitcher.

I have not described or illustrated in detail, the complicated arrangement of cams, levers, dies and other parts actually employed in the wire feeding and cutting and the staple forming, driving and clinching operations, nor the means by which the book is actually clamped and unclamped in the operation of the device, these features themselves being well known and understood by those skilled in this particular art.

Referring again to the drawing, it will be seen that the stitcher head 21 of the second unit is in a different position from the stitcher head 18 of the first unit, due to the fact that the crank arm 22 of the second unit is at a different angle with reference to the shaft 6a than the crank arm 14 of the first unit is with reference to its shaft 6. It will be obvious that the relationship shown or any other relationship between the positions of heads 21 and 18 may be secured through the adjustment of the coupler 10 with reference to the coupler 9, and that these adjustments may both be regulated or timed with reference to the position of the heads 18 and 21 with respect to the book 20 through an adjustment of the coupler 7 with respect to the coupler-gear 5. It is also evident that if for any reason it should be desired to drive the shaft 6a of the second unit from the main drive shaft, direct, instead of through a connection to such main drive shaft by way of the shaft 6 of the first unit, it would be feasible to mount on the shaft 6a a second coupler-gear similar to 5 and make it cooperate with a fixed coupler on the shaft 6a corresponding to the coupler 7. There would here again be a capacity for adjustment and timing of all units with respect to each other, with respect to the common source of power and with respect to the conveyor and the books advanced thereby.

I claim:

1. Means for spacing and applying staples to the backs of books in the binding thereof, comprising a book race along which travel the books to be stitched, a book conveyor for advancing the books along the race, a source of power common to the conveyor and a plurality of stitching heads cooperating therewith, each head being timed with reference to

the point on the books at which the staple is to be applied by that head as the books are advanced by the conveyor, through an adjustment of the driving connections between the 5 heads and the source of power.

2. Means for spacing staples applied to the backs of books in the binding thereof, comprising a conveyor for advancing the books through the stitcher and a source of power 10 common to such conveyor and a plurality of stitching heads, the first head being driven from the source of power through an adjustable arcuate coupling while each succeeding head is driven from the power shaft of the 15 head before it through a similar adjustable arcuate coupling.
